UNITED STATES PATENT OFFICE.

WILLIAM A. RINGLER, OF PHILADELPHIA, PENNSYLVANIA, ASSIGNOR TO IDA LOIS RINGLER, OF PHILADELPHIA, PENNSYLVANIA.

THRIFT SYSTEM.

Application filed March 9, 1922. Serial No. 542,511.

To all whom it may concern:

Be it known that I, WILLIAM A. RINGLER, a citizen of the United States, residing at Philadelphia, county of Philadelphia, State 5 of Pennsylvania, have invented a new and useful Thrift System, of which the following is a specification.

My present invention comprehends a novel thrift system and savings which although 10 not limited to such use is especially designed to be employed by bankers and their depositors in order that an accurate record may be kept by the bank and also by the depositor of the amount paid in and thereby eliminate 15 a complicated system of records which it has heretofore been deemed necessary to employ.

My invention also comprehends the novel instrumentalities employed such as a depositor's book of novel construction and a novel 20 card for recording deposits which co-operates with the depositor's book in such a manner that the receipt of a deposit can be simultaneously indicated both on the depositor's book and on the record card.

It further comprehends a novel recapitulation sheet showing the daily summary of all of the deposits.

Other novel features of construction and 30 advantage will hereinafter more fully appear in the detailed description.

For the purpose of illustrating my invention, I have shown in the accompanying drawings a typical embodiment thereof 35 which is at present preferred by me, since this embodiment will be found in practice to give satisfactory and reliable results. It is, however, to be understood that the various instrumentalities of which my invention 40 consists can be variously arranged and organized and that my invention is not limited to the precise arrangement and organization of these instrumentalities as herein shown and described.

Figure 1 represents, in perspective, a depositor's receipt book, embodying my invention.

Figure 2 represents a rear perspective of Figure 1.

Figure 3 represents the depositor's receipt book in front elevation showing the first page.

Figure 4 represents a depositor's book in front elevation showing two of the pages 55 open.

Figure 5 represents a top plan view of the record card.

Figure 6 represents a bottom plan view of the bank's record card.

Figure 7 represents a top plan view showing more particularly the manner in which the pages of the depositor's receipt book and the bank record card co-operate to receive the receipt stamp. 60

Figure 8 represents another view of the 65 parts seen in Figure 7.

Figure 9 represents a form of receipt which is on the last page of the depositor's receipt book.

Figure 10 represents a plan view of the 70 stamp used to simultaneously receipt the payment received on both the depositor's book and the bank record card.

Figure 11 represents a plan view of a recapitulation sheet. 75

Similar numerals of reference indicate corresponding parts.

Referring to the drawings, 1 designates a depositor's receipt book embodying my invention which has indicated 80 on the front page the number of the book as at 2, a representation of a mile stone, as at 3, and on said mile stone is indicated the percentage of interest to which the depositor is entitled and also the amount which 85 for purpose of illustration is illustrated as fifty dollars. This front page also has indicated thereon the name and address of the depositor, the name and address of the banker who issues the book and any other 90 desired advertising matter. The front page or cover has connected to it a rear page 4, see Figure 2, on which is indicated the rules and regulations under which the deposits are to be made, these rules and regulations may be 95 as follows:—

“\$1.00 deposit must be made each week but more than \$1.00 may be deposited and more than one thrift mileage account may be opened by one depositor.

A deposit of 90¢ is required each fifth week at which time 10¢ interest will be credited to you.

After the fiftieth mile you will have deposited in cash \$49.00 and you will have 105 been credited with interest of \$1.00. There is thus on deposit to your credit \$50.00.

This amount will be paid to you on demand in cash after the expiration of one year from the date of the first de- 110

posit against surrender of this thrift mileage book.

Money deposited may be withdrawn before thrift mileage is paid up in full or before the expiration of one year from the date of the first deposit but the interest credits shall become forfeited.

Interest of \$1.00 will be credited semi-annually on all paid up thrift mileage accounts not withdrawn at time of maturity.

Regular weekly deposits are necessary to receive interest credits.

This account is not transferable or negotiable.

Secured between the rear cover 4 and the front cover 5 are a series of coupons 6 certain of which have designated thereon the word "deposit" and "\$1.00" and all of these coupons are numbered. The coupons are numbered 1 to 50 and additional coupons 7 are provided for the last coupon page which have indicated thereon the interest to which the depositor is entitled in case the account is left with the bank from year to year.

Every fifth coupon, as indicated at 8, see Figures 3 and 4, instead of having the dollar deposit indicated has thereon the printed matter "deposit 90¢ interest credit 10¢."

9 designates the bank's receipt slip or record card, see Figures 5 and 6, the front face of said card having indicated thereon the number, as at 10, the amount, as at 11, the name and address, as at 12, the signature of the applicant, as at 13, and also the statement "I hereby agree to rules and regulations of thrift mileage."

The front face of the bank's record card 9 is divided into a number of squares 14 each of which is numbered and each slip at the bottom, as at 15, has also indicated thereon "interest 10¢." The back of the bank's record card 9, see Figure 6, is also divided up into a series of ruled squares 16 each of which is numbered and the squares 17 at the bottom of the card have indicated thereon "interest 10¢."

The squares at the right hand side of the card on its back are numbered 51 to 55 corresponding to the coupons 7 and have indicated thereon the word "interest." The back of the last coupon slip forms a receipt slip to be signed by the depositor when the account is closed by the bank, see Figure 9.

18 designates the receipt stamp, a bottom plan view of which is shown in Figure 10, from which it will be seen that on one side the name of the banker is indicated, as at 19, the word "received" as at 20, and the date as at 21. The opposite side is the same date as 21 and the word "received" as at 22, with ruled lines to receive the name of the receiving teller.

Assuming now that the bank deposit book 1 has been given out to the depositor and he brings the dollar to the bank to be paid

in on his account, the banker or receiving teller places the bank's record card 9 beneath the first page of the coupon book, as indicated in Figure 7, so that the coupons 1 to 5 will register with but lie at the side 70 of the spaces 1 to 5 on the record card 9. The banker then takes the stamp 18 which has been adjusted to the date on which the deposit was made and then stamps the receipt in one operation on the first coupon of 75 the depositor's receipt book and at the same time also on the first space of the bank's record card 9, so that on the coupon slip of the depositor's receipt book will appear the name of the banker, the word "received" 80 and the day, month and year of the payment and on the bank's record card 9 will appear the day, month and year on which the deposit is made and also the word "received" and the ruled lines 20 will extend 85 across both coupons.

The banker or the receiving teller then writes his name across both the coupon and the corresponding space of the card over the lines 20, as indicated at 23, a portion of the 90 signature appearing on the coupon and a portion on the corresponding space attached. The depositor's receipt book is returned to him, the banker's record card 9 is retained by the banker and is indicative of the 95 amounts which have been paid by the depositor. In a similar manner the receipts are made each time a payment is made by the depositor.

24 designates a recapitulation or daily 100 record sheet, see Figure 11, which is ruled to provide spaces for the deposits 25 and the withdrawals 26 and is provided with a daily 105 summary 27. The deposit portion is provided with the number of columns to receive the numbers of the deposit books on which payments have been made and also with columns to receive the numbers of the deposit books on which 90¢ has been paid and which are entitled to interest of ten cents and also 110 a column to receive the number of the deposit books on which a semiannual interest is to be given.

The withdrawal side of the daily record has a series of numbered columns which receive the account number, the interest forfeited and the amount paid out and also a daily summary of all of the accounts handled under this system showing the balance forwarded, the daily deposits, the interest 115 credits, the withdrawal, the closing balance, the number of accounts, the new accounts opened, the total number of all accounts, the accounts closed and the balance number of accounts.

It will thus be apparent that the daily record sheet will enable the banker to tell at a glance at the end of each day exactly how the accounts stand and the record card 9 will show the payments paid by depositors 130

and the date on which they are paid, so that the bookkeeping which is ordinarily necessary in keeping accounts of this character is entirely eliminated.

5 It will be apparent from the foregoing that I have invented a novel thrift system which embodies the features of advantage enumerated in the statement of the invention and in the foregoing description and 10 while I have, in the present instance, illustrated and described a preferred embodiment of it, it will be apparent that it is susceptible of modification in various particulars without departing from the spirit or 15 scope of the invention or sacrificing any of its advantages.

Having thus described my invention, what I claim as new and desire to secure by Letters Patent, is:

20 1. A thrift or saving system, comprising in combination a deposit book having numbered coupons each of which is provided with a delineated space representing a milestone, the milestones being consecutively numbered and a record card having numbered spaces to register with corresponding numbered coupons of the deposit book, whereby a coupon and its corresponding numbered record card space can be simultaneously received.

25 2. A thrift or saving system, comprising in combination a deposit book having pages in the form of numbered coupons each of which is provided with a delineated space representing a milestone, the milestones being consecutively numbered and having a cover with a number thereon indicative of the owner of the deposit book, and a record card having thereon a number which is the 30 duplicate of the number on the deposit book and having numbered spaces arranged to register with correspondingly numbered coupons.

3. A deposit book for thrift systems, comprising a cover and pages therein in the form of consecutively numbered coupons, each coupon having indicated thereon the amount

of the deposit to be made and every fifth coupon having indicated thereon the interest credit to which the owner is entitled.

4. A deposit book for thrift systems, comprising a cover and pages therein in the form of consecutively numbered coupons, each coupon having indicated thereon the amount of the deposit to be made and every fifth coupon having indicated thereon the interest credit to which the owner is entitled, said deposit book also having coupons having indicated thereon the interest for definite periods beyond the first yearly period.

5. A thrift system, comprising a numbered deposit book having a place for the name and address of the depositor and having its pages in the form of consecutively numbered coupons, each coupon having indicated thereon the amount to be deposited and certain of said coupons having indicated thereon the interest to be credited to the depositor, in combination with a correspondingly numbered record card having a place for the name and address of the depositor and consecutively numbered spaces adapted to register with correspondingly numbered coupons of the deposit book when the record card is inserted into the deposit book, whereby the name of the receiving clerk can be written partly on a coupon and partly on a corresponding numbered record card space.

6. A thrift system, comprising a deposit book having pages in the form of consecutively numbered coupons forming an integral part of said pages and a permanent book record, in combination with a bank record card having a series of columns of consecutively numbered spaces to enable a numbered space on the card to be brought into registry with the coupon of the deposit book which has the same number.
